UNITED STATES PATENT OFFICE.

SEYMOUR A. ROUSE AND HANS C. STOCKEL, OF CHICAGO, ILLINOIS.

ARMOR-RELINER FOR TIRES.

1,385,890.

Specification of Letters Patent. Patented July 26, 1921.

Application filed April 14, 1920. Serial No. 373,895.

To all whom it may concern:

Be it known that we, SEYMOUR A. ROUSE and HANS C. STOCKEL, citizens of the United States, residing at Chicago, in the county of

5 Cook and State of Illinois, have invented certain new and useful Improvements in Armor-Reliners for Tires; and we do hereby declare the following to be a full, clear, and exact description of the invention, such as 10 will enable others skilled in the art to which it appertains to make and use the same.

This invention relates to new and useful improvements in armor reliners for tires of the character described, illustrated, and 15 claimed in U. S. Letters Patent #1,227,673 and has for one of its objects the provision of means for preventing the connecting tongues of the disks from becoming separated or detached from the disks when 20 broken, thereby obviating the danger of the tongues working through the inner liner and puncturing the inner tube.

Another object of this invention is the provision of disks arranged in spaced parallel rows and one row of disks are connected longitudinally of the device and the other disks connected transversely to each other and connected laterally to the first named row of disks so as to make the second 30 named disks very pliable laterally and will permit them to be straightened laterally if they are not straight when punched or made from a sheet of metal with uneven edges.

A further object of this invention is the provision of disks of such shape that when 35 they are assembled in an inner liner, each disk will be supported at its center as well as at its corners by the disks thereunder, so as to obviate bending of the disks first in one 40 direction and then in the other, during the use of the device, which has proven disadvantageous owing to the fact that the disks when unsupported at their centers will soon become broken owing to the metal becoming 45 crystallized from the constant bending back and forth of the disks at their centers.

A still further object of this invention is the provision of an armor reliner for tires of the above stated character, which shall 50 be simple, durable and efficient, and which may be manufactured and sold at a comparatively low cost.

With these and other objects in view as 55 will become more apparent as the description proceeds, the invention consists in certain

novel features of construction, combination, and arrangement of parts as will be herein-after more fully described and claimed.

For a complete understanding of our invention, reference is to be had to the following description and accompanying drawings, in which—

Figure 1 is a transverse sectional view illustrating a tire with an armor reliner within the same and overlying the inner tube and constructed in accordance with our invention.

Fig. 2 is a fragmentary plan view illustrating one of the armor plates or members and the manner of connecting the various disks together.

Fig. 3 is a similar view illustrating a pair of armor members or plates arranged one over the other and showing how the outer rows of disks can have lateral movement in relation to the center or main row of disks,

Fig. 4 is a detail view drawn on an enlarged scale, illustrating the specific construction of the tongues for connecting the disks together,

Fig. 5 is a fragmentary plan view, illustrating another form of armor member or plate,

Fig. 6 is a similar view illustrating a pair of said armor members or plates arranged one over the other.

Referring in detail to the drawing, the numeral 1 indicates a tire or shoe of ordinary construction which has arranged therein the inner tube 2 that is inflated to support the shoe 1. The invention which is an improvement over the patent heretofore referred to is arranged between the inner tube and the shoe for the purpose of preventing the inner tube from being punctured and also obviating blow-outs of said shoe. The inner liner 3' consists of plies of uncured rubber impregnated cotton fabric 2' which are placed one on the other and stretched over a core so as to fit an inflated tube. A pair of armor members or plates 3 are covered with layers of rubber 4' and also a layer of rubber 5' is placed between the plates 3 and said plates and layers of rubber are positioned on the plies of fabric 2' and covered by a layer of fabric 6' and then subjected by a vulcanizing process to cause the layers or plies of fabric and rubber to adhere to each other about the armor members or plates. The plies of rubber and

fabric are of different widths so that when assembled and vulcanized together, the edges of the liner are comparatively thin.

Each of the armor plates or members is 5 constructed from steel or similar material and each consists of a plurality of substantially rectangular or square disks 4 arranged in parallel rows. The main rows 5 of disks are connected together longitudinally by 10 tongues 6, while the other rows of disks are connected transversely by tongues 7 and also connected laterally to the main rows 5 of the disks by tongues 8, so that the outer rows of disks are free to have lateral movement in 15 relation to each other and in relation to the main row, which will permit said rows of disks to adjust themselves to a straight edge. This is very essential in that it is almost impossible to secure sheet steel cut with 20 straight edges and the disks being of square or rectangular shape, also will when assembled more readily form a straight edge which is not as readily obtainable by circular or oval disks as in the patent referred to.

25 The tongues each decrease in width toward their centers so as to make the weakest points of the tongues at their medial portions and in case they break during the use of the device, the ends of the tongues will 30 remain integral with the disks, thereby obviating any danger of loose or small particles of steel within the inner liner which would be very disadvantageous in that the 35 small particles of steel would be liable to puncture the inner tube 2.

When arranging the armor plates or members one above the other, the main row of disks 5 which are connected longitudinally are arranged an even distance upon each side 40 of the center of the tread of a tire and the disks of the outer armor plate or member closes the spaces between the disks of the inner armor plate or member. When the plates or members are so assembled or arranged in relation to each other, the upper 45 rectangular or square disks rest upon the inner disks of the inner armor plate or member and are supported at their centers as well as at their corners by said disks so as 50 to prevent the disks from being bent first in one direction and then in the other which would cause said disks to become broken owing to the steel becoming crystallized by such movement.

55 By having the disks rectangular or square gives them a greater bearing surface on each other than it is possible to obtain with other shapes of disks, and avoids the weakness caused by punching so much of the material

out between the disks as in the case of forming round disks and which do not have as much bearing surface on each other. The weakest point in round disks is where the edge of one overlaps the edge of the one under it and their unsupported centers. 60 Such slight overlapping causes these edges 65 frequently to break off forming loose particles that do much more harm to the rubber and covering than larger pieces when broken, besides too much of the centers of the disks 70 are not sufficiently supported.

Referring to Figs. 5 and 6 which illustrate another form of our invention, the disks 9 are arranged in diagonal and parallel rows and the disks of each row are connected by tongues 10 similar in construction to the tongues of our other form of invention. The diagonal rows of disks are connected by tongues 11 to form armor plates or members which are placed one over the 75 other. The disks 9 are rectangular in shape and when the armor plates or members constructed from said disks are placed one over the other, the corners of the disks are supported by the disks thereunder and also the 80 spaces between said disks are closed.

While we have shown and described the preferred embodiment of our invention, it will be understood that minor changes in construction, combination, and arrangement 90 of parts may be made without departing from the spirit and scope of the invention as claimed.

Having thus described our invention, what we claim is:

95 1. An armor for tires comprising a pad, plates embedded in said pad and each including rows of square disks, tongues connecting some of said disks longitudinally, tongues connecting other of said disks transversely, said tongues having their medial portions reduced in width so that when broken they will break at their medial portions and remain attached to the disks.

100 2. An armor for tires comprising a pad, plates embedded in said pad and each including rows of square disks, tongues connecting the disks of each row, and tongues connecting some of the disks of one row to the disks of the adjacent rows, said tongues 105 having their medial portions reduced.

110 In testimony whereof we affix our signatures in presence of two witnesses.

SEYMOUR A. ROUSE.
HANS C. STOCKEL.
